UNITED STATES PATENT OFFICE.

CLAUDE C. CRASWELL, OF WHITING, INDIANA, ASSIGNOR TO STANDARD OIL COMPANY, OF WHITING, INDIANA, A CORPORATION OF INDIANA.

CANDLE BASE.

Application filed February 20, 1922. Serial No. 537,929.

To all whom it may concern:

Be it known that I, CLAUDE C. CRASWELL, a citizen of the United States, residing at 241 Laporte Avenue, Whiting, in the county 5 of Lake and State of Indiana, have invented a new and useful Improvement in Candle Bases, of which the following is a specification.

The present invention relates to candle 10 bases or candle sticks and will be more fully understood from the following description, illustrated by the accompanying drawings, in which:

Figure 1 is an elevation, partly in section, 15 of a candle base constructed in accordance with the present invention, and

Fig. 2 is a plan view of the candle base of Figure 1.

In accordance with the present invention, 20 a candle base or stick is constructed with its surface of wax, preferably paraffin wax having a melting point of at least 126° F. or mixtures of such wax with other waxes or wax-like material, such as carnauba wax, bees-wax, stearic acid, petrolatum or the like. The body of the candle base or stick may 25 suitably be formed entirely of wax, as indicated in the drawing, in which the numeral 5 designates the body of the candle stick or

30 base and the numeral 6 the opening provided therein for the reception of the candle. Such a candle base may be made by casting a round block of wax and turning it down to the desired shape for the candle base. It

is readily apparent that any form of 35 strengthening inserts may be employed, if desired, for example, of metal, fabric, wood, or any other suitable material.

A candle base constructed in accordance with the present invention, and having a 40 surface formed entirely of wax, matches the candle employed in connection with it in texture and translucency, and can be colored, or dipped in the same manner as the candle thereby acquiring an external appearance 45 closely corresponding to that of the candle itself, this being impossible with candle sticks of the usual construction of other materials with applied designs or color patterns. For example, when used with multi-colored 50 candles coated in the manner described in the co-pending application of Jesse G. Brinker and Claude C. McNeil, Serial No. 486,046, filed July 20, 1921, the wax surface 55 candle base can be dipped or coated in a similar manner and with the same or harmonizing colors.

It is readily apparent that the candle may be made of wax of uniform color throughout, or wax of several colors may be employed in this manufacture to produce a candle base having colored designs thereon, or of mottled appearance.

I claim:

As an article of manufacture, a candle holder formed from wax and adapted to receive and removably support a wax candle.

CLAUDE C. CRASWELL.
